FOLDING TOOTHBRUSH

Ted R. Stacey and Roy H. Lesner, Chicago, Ill., assignors, by mesne assignments, to Totebrush, Inc., Chicago, Ill., a corporation of Illinois

Original application April 26, 1946, Serial No. 665,237, now Patent No. 2,503,924, dated April 11, 1950. Divided and this application February 20, 1947, Serial No. 729,778

5 Claims. (Cl. 15—144)

1

This invention relates to toothbrushes, and particularly to a toothbrush adapted to be folded and combined with a receptacle which may have a compartment for powdered dentifrice or a tube of the same in paste form, the assembly being small and compact and hence adapted for use by travelers and others to whom compactness and ease of portability are important considerations. The toothbrush has utility, however, apart from the receptacle.

This application is a division of our co-pending application Serial Number 665,237, filed April 26, 1946, now U. S. Patent No. 2,503,924.

One principal object of the invention is to provide a folding toothbrush having a handle portion and a brush portion foldable with respect to one another, and novel means for locking the portions in extended position whereby a brush having substantially the same rigidity as a conventional toothbrush results, such means including members slideable with respect to the handle portion and engageable over two opposed faces of the brush portion.

Another object is to provide a folding toothbrush having a handle portion and a brush portion hinged together and including a latch for locking the parts in extended, i. e., operative, position, the actuating part of the latch being so formed as to constitute a convenient and comfortable part of the handle.

Other objects will appear as the description proceeds.

In the drawing illustrating one embodiment of our invention:

Fig. 1 is a perspective view of the toothbrush in partially unfolded position;

Fig. 2 is a side-elevational view of the folded brush;

Fig. 3 is a side-elevational view of the brush in extended position, and locked;

Fig. 4 is a plan view of the brush as shown in Fig. 3;

Fig. 5 is a partly elevational and partly cross-sectional view of the brush in the position of Fig. 3;

Fig. 6 is a cross-sectional view taken on the line 6—6 of Fig. 5; and

Fig. 7 is a detail view in perspective of the latch operating pad.

Turning to the drawing, the brush includes two principal parts hereinafter for convenience referred to as the brush part 11 and the handle part 12. Part 11 includes a body portion 13 made of any suitable material, e. g., plastic composition, and has embedded therein the plurality of tufts

2

of bristles 14, the transverse cross-sectional contour of the body being preferably substantially rectangular as shown. The handle part 12, including a body portion 15, is of similar material and transverse cross section, and each of the parts 13 and 15 is provided at their juxtaposed ends with ears 16—16 and 17—17 through apertures in which pass the pivots 18—18 to form a hinged connection, whereabout the parts 11 and 12 may be folded into the compact form shown in Fig. 2.

To maintain operative alignment of parts 11 and 12, there is provided latch means including a pad 21, a finger 22, and a screw 23, all slideable as a unit with respect to body portion 15. Finger 22 is preferably of stainless steel for strength and resistance to rusting, and is slideable in aligned recesses 24 and 25 in the portions 15 and 13, respectively. Screw 23 is preferably of stainless steel, is shouldered to abut the finger 22 (Fig. 6), and is threaded thereinto, the head of the screw lying in a counterbored part 26 of aperture 27 passing through the pad 21. Thus finger 22 is slideable longitudinally of the brush upon corresponding sliding movement of pad 21. It is to be noted that by sinking the finger 22 within the recess 24, a flush surface is provided on the rear face of the unfolded brush, and with this the absence of objectionable projections, which would prove uncomfortable to the user. Moreover it is to be noted that the latch operating pad is curvilinear on its exterior face to fit comfortably within the fingers of the user. To afford clearance for the shank of the screw 23, the portion 15 is longitudinally slotted at 31, and to guide the pad 21 the portion 15 (Fig. 7) and pad 21 are provided respectively with intermatting tongues 32—32 and grooves 33—33. To insure against unintended loosening of the screw 23 the threaded end thereof may be slightly peened over as is well known.

Accordingly, when pad 21 is to the right, as seen in Fig. 5, the pad 21 and finger 22 lie against opposite faces of the brush portion 13 to retain the same in extended position with respect to the handle portion 12; and when pad 21 is moved to the left, the pad and finger are freed from engagement with portion 13 to permit the latter to be folded about handle portion 15 and into the position of Fig. 2. If desired, the outer convex face of pad 21 may be corrugated or knurled for more positive engagement by the fingers.

One of the outstanding advantages of the instant construction resides in utilizing both the latch and the latch operating pad to render the unfolded brush rigid while in use. Thus, referring

to Fig. 5 it is noted that the finger 22 and pad 21, when in locking position, embrace between them the brush portion 13, and by careful fitting of the parts, i. e., providing minimum sliding clearance, the brush portion 13 may be made quite rigid with respect to the handle portion 15.

To secure the brush snugly within a case or receptacle (for example, as shown in our co-pending application referred to) the handle portion 15 may be provided with protrusions 48 (Fig. 4) on the handle portion to engage corresponding depressions in the receptacle, the inherent elasticity of the walls thereof permitting such engagement and subsequent easy disengagement.

From the foregoing it will be comprehended that we have provided a sturdy, inexpensive foldable brush, having a minimum number of parts, and which, when in operative position, is characterized by all of the rigidity of a one-piece structure.

While we have shown particular embodiments of our invention, it will be understood, of course, that we do not wish to be limited thereto since many modifications may be made, and we therefore contemplate by the appended claims to cover any such modifications as fall within the true spirit and scope of our invention.

Having thus described our invention, what we claim and desire to secure by Letters Patent is:

1. A folding toothbrush comprising a handle portion and a brush portion, hinge means interconnecting said portions whereby said portions may be folded and unfolded, means for locking said portions in unfolded position including a member slidable with respect to the handle portion and engageable over one face of the brush portion and a second member secured to and slidable with said first member and engageable over the opposite face of the brush portion, said portions each having a slot therein together forming a continuous channel for receiving said first member flush with respect to the surface of said portions.

2. A folding toothbrush comprising an elongated handle portion and an elongated brush portion, hinge means interconnecting said portions whereby said portions may be folded and unfolded about the axis of said hinge means, said portions having aligned, intercommunicating superficial recesses longitudinally thereof and positioned on the same side of the brush as said hinge means, a latch member frictionally engaged in said recesses for sliding movement therein for locking the brush in unfolded position, means frictionally abutting said portions, when said latch member is in locking position, for operating said member, one of said portions having a slot therethrough, and a rigid connection between said means and member, extending through said slot.

3. A folding toothbrush comprising an elongated handle portion and an elongated brush portion, hinge means interconnecting said portions whereby said portions may be folded and

unfolded about the axis of said hinge means, said portions having aligned, intercommunicating recesses longitudinally thereof, a latch member frictionally engaged in said recesses for sliding movement therein for locking the brush in unfolded position, a movable pad frictionally abutting said portions, when said latch member is in locking position, for operating said member, a rigid connection between said pad and member, and interengaging elements on said handle portion and pad for guiding said pad during movement in a direction longitudinally of the brush, said latch member being disposed adjacent one face of said portions and said pad being disposed adjacent the opposite face thereof.

4. A folding toothbrush comprising an elongated handle portion and an elongated brush portion, hinge means interconnecting said portions whereby said portions may be folded and unfolded about the axis of said hinge means, each said portion having at least one flat face, the faces being in juxtaposition when the brush is folded and co-planar when the brush is unfolded, said faces having intercommunicating aligned recesses longitudinally thereof, and a latch member lying wholly within the recesses and slidable therein for locking the portions in unfolded position, and means for sliding said member, said means including an elongated member straddling said portions on the side opposite said faces when said latch is in locking position.

5. A foldable toothbrush comprising a brush portion including a plurality of bristles, and a handle portion, a hinge interconnecting said portions end to end whereby said portions may be folded one upon the other, means for rigidly locking said portions in unfolded relation, said means including an elongated slidable member substantially equal in length to said handle portion, a latching finger longitudinally substantially coextensive with said member, said member being contiguous to one face of the toothbrush and said finger being contiguous to the opposite face thereof, and a pin rigidly uniting said member and finger for joint movement to locking and unlocking position, said handle portion having a slot for the reception of said pin the locking relation being such that said member and finger form a bifurcated support rigidly embracing said brush portion between the furcations thereof.
